CLOTH GUIDE

William M. Phelps, Chatsworth, Ga., assignor to
 Chatsworth Manufacturing Co., Chatsworth,
 Ga., a partnership

Application July 9, 1952, Serial No. 297,809

4 Claims. (Cl. 26—67)

1

My invention relates to a cloth guiding device. A primary object of the invention is to provide a cloth guiding apparatus or device for use with cloth finishing machines, such as brushes, shears, winding machines and the like, the device serving to prevent lateral deviations in cloth travel while simultaneously spreading the cloth transversely and preventing the same from wrinkling during its advancement.

A further object is to provide a cloth guiding device having a novel and simplified construction, and a new mode of operation.

Other objects and advantages of the invention will be apparent during the course of the following description.

In the accompanying drawings, forming a part of this application, and in which like numerals are employed to designate like parts throughout the same,

Figure 1 is a side elevation, partly diagrammatic, of a cloth winding machine having my guiding device embodied therein, parts in section,

Figure 2 is a plan view of the cloth guiding device in a normal or intermediate operative position,

Figure 3 is a further plan view of the device in the operative position for automatically correcting or controlling lateral travel of the cloth,

Figure 4 is an enlarged transverse vertical section on line 4—4 of Figure 1,

Figure 5 is an enlarged vertical section on line 5—5 of Figure 2,

Figure 6 is a fragmentary bottom plan view of the cloth guiding device, and,

Figure 7 is an enlarged fragmentary side elevation of one guide roller and holder.

In the drawings, where for the purpose of illustration is shown a preferred embodiment of the invention, attention is directed first to Figure 1 which illustrates a cloth winding machine having embodied therein my cloth guiding device 10. In the machine shown in Figure 1, cloth 11 is unwound from a roll 12 and rewound upon a roll 13. A weight 14 provides friction for the roll 12, and one or both of winding cylinders 15 which support the roll 13, is positively operated for rotating the roll 13. The cloth 11 during its movement in the direction of the arrows engages a plurality of guide rolls 16, arranged so that the cloth passes horizontally through the guide device 10, as shown in Figure 1.

The guide device 10 comprises a stationary horizontal transverse mounting bar 17, long enough to extend entirely across the cloth 11 and somewhat beyond the longitudinal edges thereof. Near its opposite ends, the bar 17 has adapters

2

or blocks 18 rigidly secured thereto by any suitable means. The blocks 18 engage the corresponding vertical sides of fixed posts or uprights 19, and are rigidly secured thereto by bolts 20 or the like. The posts 19 are arranged outwardly of the longitudinal edges of the cloth 11 and extend above the horizontal run of the cloth as shown in Figure 1, for supporting the bar 17 in vertically spaced relation to the cloth.

Trunnion blocks or bearings 21 are rigidly secured to the mounting bar 17 and spaced inwardly of the opposite longitudinal edges of the cloth 11 for equal distances, as shown. Guide roller brackets or holders 22 are arranged adjacent to the bottoms of the trunnion blocks 21 and pivotally secured thereto for free horizontal swinging movement by screws 23 or the like. The brackets 22 are bodily mounted upon the trunnion blocks 21 by means of the screws 23.

The brackets 22 are horizontally elongated, as shown, and include horizontal tops 24 which underlie the stationery mounting bar 17. The pivot screws 23 engage the brackets 22 near their inner ends 25, Figure 4, and the bracket ends 25 are spaced inwardly of the longitudinal edges of the cloth 11. The brackets 22 further comprise outer depending ends 26, integral therewith and spaced slightly outwardly of the longitudinal edges of the cloth 11. The lower ends of the bracket ends 26 are arranged substantially at the elevation of the cloth 11, Figures 4 and 7, and the inner and outer bracket ends 25 and 26 are arranged in spaced opposed relation as shown. Spiked cylindrical guide rollers 27 are carried by the brackets 22 and disposed horizontally beneath the bracket tops 24 and between the ends 25 and 26. The rollers 27 have their ends freely journaled upon screws 28 and 29, secured within openings formed in the bracket ends 25 and 26. The guide rollers 27 extend longitudinally of the brackets 22 for the major portion of the lengths of the latter, and the rollers are provided at their outer ends with integral undercut extensions 30 forming annular shoulders 31. The rollers 27 are also preferably provided at their inner ends with undercut extensions 32, integral therewith and slidably contacting the adjacent bracket ends 25. The radial spikes or pins of the guide rollers 27 project below the bottoms of the bracket ends 25 and 26, for penetrating engagement with the cloth 11.

Flat horizontal blades or keepers 33 extend beneath the guide rollers 27 throughout substantially their entire lengths, and the outer ends of the blades 33 are rigidly secured to the bottoms 55 of the bracket ends 26 by screws 34. The opposite

ends of the blades 33 are free from connection with the brackets 22 so as to provide narrow passages beneath the guide roller 21 for the marginal portions of the cloth 11, Figure 4. The blades 33 are preferably somewhat resilient, although they are relatively stiff, and serve to hold the cloth 11 in positive engagement with the spiked guide rolls.

Inwardly directed tongues or plates 35 are interposed between the bracket ends 26 and blades 33 and have openings receiving the screws 34, which rigidly secure the tongues 35 in place. Inwardly of the bracket ends 26, the tongues 35 are upwardly inclined slightly as at 36, Figure 7, and the inner inclined ends of the tongues 35 engage the shoulders 31 of the guide rollers and prevent end play of the latter. The inclined tongues also form with the horizontal blades 33 recesses or grooves 37 into which the adjacent longitudinal edges of the cloth 11 may travel when the cloth tends to deviate or wander laterally during the winding operation. The brackets 22 and guide rollers 21 are generally parallel to the fixed mounting bar 17, as shown, but are adapted to adjust themselves angularly with respect to the bar 17, as will be further described hereinafter.

Horizontal arms 38 are rigidly secured to corresponding sides of the brackets 22 near their inner ends, and these arms 38 are perpendicular to the brackets 22 and guide rollers and extend generally longitudinally of the cloth 11. The arms 38 are of equal length, as shown, and freely swingable horizontally with the brackets 22 and guide rollers 21. The arms 38 are pivotally connected near their ends remote from the brackets 22 to the bottoms of bearing blocks 39, by means of screws 40. The bearing blocks 39 have openings 41 formed therein for receiving a horizontal transverse connecting or tie rod 42. The tops of the blocks 39 are provided with slots 43 leading into the openings 41, and clamp screws 44 serve to adjustably rigidly secure the bearing blocks 39 to the tie rod 42, as shown. The tie rod 42 is generally parallel to the fixed bar 17 in all adjusted positions, but is bodily shiftable in a horizontal plane with the arms 38 during the operation of the guide device.

In use, the bearing blocks 39 are adjusted longitudinally on the tie rod 42 until the arms 38 converge rearwardly slightly, as shown in Figure 2. The brackets 22 and the guide rollers 21 are now arranged at slight equal angles with respect to the transverse bar 17 and have their outer portions extending rearwardly beyond the bar 17. The rollers 21 are therefore rearwardly inclined toward their outer ends with respect to the longitudinal axis of the cloth 11.

The cloth 11 is fed longitudinally between the guide rollers 21 and blades 23 during the winding operation, and as the cloth moves in the direction of the arrows, the spiked guide rollers are rotated by the cloth. The angularly disposed guide rollers tension the cloth transversely and maintain it free of wrinkles as they guide the cloth in a straight line and minimize any tendency for the cloth to deviate laterally during the winding.

When the cloth does deviate laterally in one direction, as shown in Figure 3, my guide device functions automatically to correct lateral deviation and return the cloth to the proper straight line travel shown in Figure 2. With the cloth deviating laterally, in the direction of the top of Figure 3, the longitudinal edge of the cloth 11 toward the direction of deviation enters the

groove 37 of the adjacent guide roller bracket 22. The engagement of the edge of the cloth in this groove 37 swings the adjacent bracket 22, at the top of Figures 2 and 3, forwardly upon its pivot 23 and this bracket and its guide roller 21 are shifted to the forward angular position, with the outer end of the bracket extending upon the forward side of the bar 17. The arm 38 near the top of Figure 3, now moves rod 42 toward the bottom of Figure 3, and the other bracket 22 is swung rearwardly from the normal rear position to a further rear position with respect to the bar 17. When the two rollers 21 are thus angularly adjusted, as the cloth is pulled forwardly, it will be shifted laterally from the deviated position toward the bottom of Figure 3 and returned to the normal transverse central position. The action of the cloth returning to the normal position, causes the rollers 21 to return to the normal position, Figure 2. Should the cloth deviate laterally in an opposite direction, toward the bottom of Figure 3 of the drawings, then the bracket 22 at the bottom of Figure 2 would swing forwardly so that its outer end would be arranged upon the forward side of the bar 17, and the bracket 22 at the top of Figure 2 would be swung rearwardly so that its outer end would be moved further from the bar 17. The action of the angularly adjusted rollers 21 carried by the brackets 22 would then shift the cloth laterally in an opposite direction, toward the tops of Figures 2 and 3 and the cloth would be returned to the normal position. In each case of lateral deviation of the cloth, as soon as the longitudinal edge of the cloth contacts sufficiently with the tongue 35, upon entering the groove 37, the simultaneous swinging of the brackets 22 occurs and the correcting action of the cloth guide commences. The device will function automatically to maintain a true straight line travel in the cloth 11, with lateral deviations so slight that they are unobjectional. The lateral deviation shown in Figure 3 is greatly exaggerated, merely for the purpose of illustrating the operation of the device, and in practice substantially no lateral deviation will occur due to the control afforded by the guiding device. As previously stated, the guiding device 10 maintains the cloth 11 flat and taut transversely, so that it cannot wrinkle during the winding operation.

It is to be understood that the form of the invention herewith shown and described is to be taken as a preferred example of the same, and that various changes in the shape, size and arrangement of parts may be resorted to, without departing from the spirit of the invention or scope of the subjoined claims.

Having thus described my invention I claim:

1. Cloth guiding means comprising a relatively stationary support, guide devices pivoted to the support near the longitudinal edges of the cloth and having passages receiving the longitudinal edges of the cloth and parts to be engaged by said longitudinal edges when the cloth deviates laterally, arms secured to the guide devices and extending beyond corresponding sides of the same, and an element connecting the arms for causing them to turn the guide devices in the same direction in unison and change their angles relative to the longitudinal edges of the cloth when the cloth deviates laterally and engages one of said parts of the guide devices.

2. Cloth guiding apparatus comprising a relatively stationary supporting bar extending transversely of the cloth and spaced from one face of

the same, holders pivotally secured to the bar for swinging movement between the bar and cloth and positioned near the longitudinal edges of the cloth, guide rollers journaled upon the holders and disposed at angles to the longitudinal edges of the cloth and engaging the cloth, the holders having parts engageable with the longitudinal edges of the cloth when the cloth deviates laterally for causing the holders and guide rollers to turn upon their pivots, and connecting means for the holders so that they will turn with the guide rollers in unison when the cloth deviates laterally, whereby the guide rollers will assume unequal angles to the longitudinal edges of the cloth and cause the cloth to return automatically to a straight line of travel.

3. A cloth guiding apparatus comprising, a support arranged near one face of the cloth, holders arranged adjacent to said face and extending transversely thereof, means to pivotally mount the inner ends of the holders upon the support, the outer ends of the holders being arranged adjacent to the longitudinal edges of the cloth, means mounted upon and arranged adjacent to the outer end of each holder for forming a grooved element for receiving the edge of the fabric when it deviates laterally so that the movement of the fabric will swing the outer end of the holder in the direction of travel of the fabric, rollers carried by the holders and extending longitudinally of the holders, arms secured to the holders adjacent to their pivots and

arranged upon the same side of the holders, and a rod pivotally connected with the arms.

4. A cloth guiding apparatus comprising, a support arranged near one face of the cloth, holders arranged adjacent to said face and extending transversely thereof, means to pivotally mount the holders upon the support so that the outer ends of the holders may be swung forwardly with relation to the travel of the cloth, the outer ends of the holders being arranged adjacent to the longitudinal edges of the cloth, rollers carried by the holders and extending longitudinally of the holders, means mounted upon each holder and including an element disposed opposite the roller, said element including a grooved part arranged adjacent to the outer end of the holder for receiving the edge of the fabric when it deviates laterally so that the movement of the fabric will swing the outer end of the holder in the direction of travel of the fabric, arms secured to the holders, and a rod pivotally connected with the arms.
